UNITED STATES PATENT OFFICE.

NATHANIEL H. VAN WINKLE, OF NEW YORK, N. Y.

BED-LOUNGE.

SPECIFICATION forming part of Letters Patent No. 272,991, dated February 27, 1883.

Application filed December 29, 1882. (No model.)

To all whom it may concern:

Be it known that I, NATHANIEL H. VAN WINKLE, a citizen of the United States, residing in New York city, State of New York, have 5 invented certain new and useful Improvements in Bed-Lounges; and I do declare the following to be a full, clear, and exact description of the invention, such as will enable others skilled in the art to which it appertains to make and 10 use the same, reference being had to the accompanying drawings, and to the letters and figures of reference marked thereon, which form a part of this specification.

My invention relates to bed-lounges; and the 15 improvement consists solely in the manner of adjusting the head-rest when the lounge is used as a bed or couch.

Heretofore great difficulty has been experienced in getting the head-rest on the under 20 part of the lounge on the same incline as the inclined head of the extension, and thus form one continuous head-rest, without at the same time increasing the height of the head when the lounge is closed up. This object is partly 25 accomplished in the lounge patented to James K. Stockton and Milo S. Stockton, November 9, 1875, No. 169,862; but in the Stockton lounge only the lower part of the head is raised, the upper portion remaining always at the same 30 height. In my improvement the whole head-rest is raised to the same level as the inclined head of the lounge.

In the accompanying drawings, in which similar letters of reference indicate like parts, Figure 1 is a perspective view of an open bed-lounge containing my improvement. Fig. 2 is a section through the open lounge on the line $x'y$, showing the head-rest adjusted for the bed. Fig. 3 is a section through the lounge 40 on the line xy , and shows the head-rest dropped into a position ready for closing the bed preparatory to transforming it into a lounge.

C. C is the main frame of the lounge. D is the extension forming the seat of the lounge 45 proper and one-half of the bed when the lounge is open. E is a revolving frame containing a mattress and fitted into the main frame. F is

the inclined head-rest of the lounge proper. G is the adjustable head-rest to and for the frame E when the lounge is converted into a bed. b 50 is the mattress or cushion on the head-rest G; b' is the mattress on the revolving frame E; d, a stop for holding the head-rest G in position. e is a support for the head-rest G when it is dropped to allow the lounge to be closed. 55 f is a support extending from front to back across the under part of the frame-work of the head of the lounge and pivoted thereto on either side at g. h h are hinges connecting the support f to the head-rest G. 60

The lounge being open, as shown in Fig. 1, the head-rest G is in the position shown in Fig. 2. In order to close the lounge, the head-rest G is pulled back, and being hinged to the support f, which is pivoted at g to the frame-work 65 of the head, it moves in the direction shown by arrow 1. The lower part of the head rest G is then moved in the direction shown by arrow 2 and the rest will be brought into the position shown in Fig. 3, when the lounge may 70 be closed up, the frame E revolving on the point k and the extension D closing over it in the ordinary manuer.

Having thus described my invention, what I claim as new, and desire to secure by United 75 States Letters Patent, is—

1. The semi-revolving support f, pivoted at one side or edge to the stationary frame of the head-rest and on the opposite side or edge thereof hinged to the adjustable head-rest G, 80 substantially as and for the purpose set forth.

2. The combination of the head-rest G with the hinges h, pivoted support f, and stop d, substantially as described.

3. The head-rest G, in combination with 85 hinges h, pivoted support f, stop d, and support e, substantially as and for the purpose described.

In testimony whereof I affix my signature in presence of two witnesses.

NATHANIEL H. VAN WINKLE.

Witnesses:

JAMES DUNN,

GEO. E. VAN WINKLE.
